VARIABLE SPEED MECHANISM

Peter J. McLaren, New York, N. Y.

Application August 20, 1937, Serial No. 160,052

22 Claims. (Cl. 74—283)

This invention relates broadly to multiple speed transmission mechanism, and more particularly to mechanism of a kind adapted to provide a very large number of transmission ratios. An apparatus of the kind referred to may, for example, comprise an input member adapted for progressive operation to any desired extent, an output member operable from the input member, a multiple speed transmission means, and a transmission ratio selector for establishing any one of a multiplicity of available driving ratios from the input member to the output member.

In accordance with known practice, a common input member is arranged to be coupled through any one or more of a number of transmission channels with a common output member, the several channels being so constructed and arranged that their individual transmission ratios form the geometrical series $1k, 2k, 4k, 8k$ (k being a constant). With these ratios available for use individually and in any desired combination of two or more, 15 transmission ratios are made possible whose relationship is such that the available ratios form the complete arithmetical series $1k, 2k, 3k \dots 15k$. A selector mechanism is provided for controlling the order of selection or coupling to cause the available ratios to be made effective, in continuously ascending or continuously descending order. These principles are desirably adhered to in the present invention.

In prior practice, the principles referred to have been susceptible of very limited application. Each transmission channel includes a primary gear on a common input shaft, which gear is adapted to be coupled to and uncoupled from the shaft by the selector mechanism, and a secondary gear in mesh with the primary gear and bearing a size relationship to the primary gear suitable to establish the characteristic ratio of the channel. The outputs of adjacent pairs of secondary gears are combined through differential gears, and the outputs of these differential gears are in turn differentially combined for transmission to the common output member.

Such a construction is expensive in a simple case because of the necessity for providing distinctive primary and secondary gears. The more serious objection, however, lies in the fact that any attempt to extend the application of the underlying principle would involve making the ratio of the primary gear to the secondary gear of each added channel twice as great as the ratio of the primary gear to the secondary gear of the channel which precedes it in the series.

The provision of gears bearing a ratio to one an-

other of 256 to 1, for example, would involve the employment of a very large gear and, because of the necessity for leading all of the channels through differential gearing to a common outlet, would necessitate the enlargement of gears and other parts all along the line.

Similar objections occur in connection with the selector mechanism heretofore employed. Such selector mechanism includes a series of cams affixed to a common selector shaft for rotation in unison, each cam controlling the coupling and uncoupling of a single one of the channels in its proper order to cause the transmission ratios successively made available to form an unbroken arithmetical series. The channel of the lowest individual transmission value must be effective for each odd ratio and ineffective for each even ratio. If, therefore, there are 15 available ratios, the cam must have 8 high spots and 8 low spots in regular alternation, which is feasible, but if there are to be 51 available ratios the cam must have 256 high spots and 256 low spots in regular alternation, which is possible only in a construction of enormous size.

It is a primary object of the present invention to provide a multiple speed mechanism which may be made compactly and economically, and which is practically capable of extension over a greatly increased range of transmission values as compared with prior structures. The invention involves important features of novelty both in the transmission mechanism itself and also in the selector mechanism.

In accordance with a practical and highly advantageous feature of the invention, a series of like differential gears is provided, the gears being mounted coaxially upon a common shaft. Each differential includes a primary input gear arranged to be individually coupled to and uncoupled from a common input or operating shaft and to be locked against operation when uncoupled. Each differential gear other than the last in the series includes an output gear through which it transmits its entire input, divided by two, to a secondary input gear of the next differential gear higher in the series. The last differential gear of the series includes an output gear which operates a common output shaft; that is to say, the entire input to all of the differential gears is transformed and transmitted through the output of the last differential gear. The first differential gear of the series has but one real input, its secondary input being always locked against operation.

Thus an input through the primary input gear

of the first differential gear passes through all of the differential gears and is cut in half once for each differential passed through. The individual input value of the first differential gear 5 may be called 1. An input through the primary input gear of the second differential is also cut in half once for each differential passed through, but since it passes through one less differential gear than the input through the first differential gear, it is cut in half one less time. The individual input value of the second differential gear is twice as great as the individual input value of the first and is, therefore, 2. Similarly, the individual input value of the third differential 10 is 4, that of the fourth is 8, and so on.

Broadly, the invention contemplates the provision of a set of transforming differential gears adapted for selective coupling in parallel through their respective primary input gears to a common rotary input member, and permanently connected in series through their output gears and their secondary input gears to a common rotary output member.

The differential gears may all be exactly alike 25 in construction. There is, therefore, no necessary limitation upon the number of transmission ratios which may be made available. Since the several differential gears may all be duplicates, moreover, the construction is inexpensive as compared with prior practice. The gears may be of 30 moderate size and the arrangement may be very compact.

The order in which the primary input gears of the several differentials are required to be coupled 35 and uncoupled in order to cause the successively available transmission ratios to form an unbroken arithmetical series may be briefly indicated. The primary input gear of the first differential should be out of action for zero, in for 1, out for 2, and 40 so on at alternate steps. The primary gear of the second differential should be out of action for zero and 1, in for 2 and 3, out for 4 and 5, and so on at alternate pairs of steps. The primary input gear of the third differential should 45 be out of action for zero to 3, in for 4 to 7, out for 8 to 11, and so on at alternate sets of 4 steps. In other words, if the individual input value of a differential is represented by 2^n power it should first be out for 2^n steps, then in for 2^n steps, and 50 so on in regular alternation.

It is not inconvenient to provide a cam unit comprising three cams for controlling the primary inputs of only three differentials, since this requires only that the cam controlling the primary input of the first differential shall have 55 four high spots and four low spots in alternation. A plurality of such units are provided. A full rotation of each unit requires a unit to be advanced through eight equal steps. Carry-over 60 mechanism is provided for operating the second unit a single step at each eighth step of the first unit, and similar carry-over mechanism is provided for operating the third unit a single step at each eighth step of the second unit. The carry-over mechanism most desirably takes the form of Geneva gearing which positively locks each higher unit against operation at all times, save the particular step or steps during which it is required to be operated.

70 The specific arrangement indicated is, of course, to be regarded merely as illustrative, since the principle of providing a plurality of selector units each operated through carry over from a selector unit of lower order may obviously be put 75 into practice in a variety of specific ways.

A selector mechanism constructed for operation in accordance with the principle outlined may consist of very simple and compact units which are duplicates of one another. A selector mechanism of this kind embodies no necessary limitation upon the number of speed ratios which may be made available.

The selector mechanism may be arranged to set up successive driving ratios which form an unbroken arithmetical series as described above, 10 or to set up a broken or interrupted series if desired.

It is a further object of the invention to provide a transmission mechanism for utilizing the broad principle heretofore pointed out, but in which 15 simple, internal, epicyclic, differential gears are employed. In simple gearing of this type it is not possible to cause each differential to divide its input by 2. A division by 4 is, however, possible. Pursuant to the attainment of the stated 20 object, two banks of differentials are desirably provided, each differential constructed to divide its input by 4, and each connected through its neighbor higher in the series to a common output shaft. The common output shafts of the respective banks are so connected to a final output shaft which is common to the two banks that one bank in its entirety has twice the weight of the other. Thus the differentials in one bank may have individual output values of 1, 4, 16, 64, etc., 25 while the differentials of the other bank may have individual output values of 2, 8, 32, 128, etc., the two banks together providing individual output values representing each power of 2.

Other objects and features of the invention 35 will appear as the description of the particular physical embodiment of the invention selected for illustration thereof progresses.

In the accompanying drawings, like reference characters have been applied to corresponding 40 parts throughout the several views which make up the drawings, in which:

Fig. 1 is a plan view of a speed changing mechanism in the construction of which the present invention has been embodied;

Fig. 2 is a view thereof in side elevation, looking from right to left on Fig. 1;

Fig. 3 is a view in vertical section, taken on the broken line 3—3 of Fig. 1;

Fig. 4 is a view in rear elevation of the mechanism shown in Figs. 1 and 3 with the rear plate removed;

Fig. 5 is a view thereof in front elevation with the front plate removed;

Fig. 10 is a schematic view in perspective of the 65 several instrumentalities of the mechanism, assembled in their combinative relationship;

Fig. 11 is a similar fragmentary detail view in stretched-out perspective of one of the differential speed-changing devices of the mechanism, illustrating its connection with the adjacent differential of the series;

Fig. 12 is a diagrammatic view illustrating a modified form of speed changing mechanism;

Fig. 13 is a fragmentary horizontal sectional 75

view showing details of the structure diagrammatically illustrated in Fig. 12; and

Fig. 14 is a fragmentary sectional detail view, taken on the line 14—14 of Fig. 13, looking in the direction of the arrows.

In the now preferred embodiment of this invention selected for illustration and description, the reference character C designates generally the casing of a speed changing mechanism, the casing being made up of front and rear plates 11 and 12, side plates 13 and 14; also a bottom plate 15 and top plate members 16 and 16x.

All of the mechanism, in the embodiment illustrated, is organized in connection with several shafts disposed in axial parallelism between the side walls or members 13 and 14, in which suitable bearings are provided which are not illustrated in detail as they may be of any suitable construction. A shaft designated 20 constitutes the main driving member of the mechanism and is hereinafter referred to as the input or driving member or driving shaft. This shaft is provided with several pinions 21 to 29 inclusive (see Figs. 3, 5 and 10), each pinion serving to impart input motion to one of a series of speed changing devices of which there are nine in the instance illustrated, although any suitable number may be provided, in accordance with the needs of any particular installation. The driving member 20 may be actuated by any suitable means, and in the instance shown such actuation is illustratively provided for by a handle 19.

The handle is shown at the left hand side of Fig. 1, but the power may be supplied from the other side with equal facility. The reference characters D1—D9 in Fig. 5 and Fig. 10 designate respectively each a speed changing mechanism constituted by a differential. Each differential includes a spider (see Figs. 3, 5, 7, 9 and 11), of which there are nine, designated 31—39 inclusive, each being fixed upon a hub 9 (see Figs. 7, 9 and 10), mounted upon a driven shaft 30, the driven shaft being common to the entire system of differentials, in the instance illustrated, and having at its end (see Fig. 5) beyond the boundaries of the casing, a gear 18 which serves illustratively as means to deliver the combined output motion of the speed changing mechanism as a whole.

Upon further reference to Fig. 7, it will be seen that the driven shaft 30 has fixed thereto, as by a pin 10, the hub 9x of the spider 39, this being the last in order of the series of spiders, the first of which, 31, forms part of the differential D1, illustrated in detail in Fig. 9, while the first four differentials, and their associated parts, are shown in a perspective assembly view in Fig. 10.

All motion communicated to the driven shaft 30 is delivered thereto through the spider 39, the hubs 9, see Fig. 7, of all of the other spiders being freely mounted relatively to the shaft 30. The rotative motion of every spider, and of each differential, is developed with respect to a stationary gear P1 of the differential D1, fixed at P in the side wall 14 of the casing, and which serves as a sun gear for a planetary pinion 41 mounted on an arm 17 of the spider 31 (see Figs. 9 and 11).

A planetary pinion 41x is carried by an arm 17x of the spider, and is in mesh both with the planetary gear 41 and with a gear 51x which forms part of a "Siamese" or duplex, primary input gear 51 to 51x having a common hub 50, best seen in Fig. 7, and in Fig. 10, where this duplex gear is shown as mounted rotatably on the hub 9 of the spider 31. Integral with this hub 9 is the secondary input member P2 of the next differ-

tial D2 in the series, and the same arrangement continues throughout the series of differentials, each comprising a structure including a spider, with its planetary pinions, the spider hub with the secondary gear of the adjoining differential, 5 and the duplex or primary input gear rotatably carried therebetween on the spider hub.

This structure is clearly shown also in Fig. 11, which illustrates also in schematic fashion the relationship between the driven shaft 30 and the 10 surrounding hub 9 of the spider, extending through the hub 50 of the duplex gears 51—51x, to the secondary input member P2 of the differential D2.

In pursuance of the invention, provision is 15 made of a series of coupling gears (see Figs. 10, 11, etc.), numbered 61 to 69 inclusive, of which one is provided for each of the differential speed changing mechanisms, and each of these coupling gears is always in mesh with the primary 20 input gear (51—59) of its particular differential, as shown in Fig. 10, where all of the coupling gears 61 to 64 are in mesh respectively with their complementary primary input gears 51 to 54 inclusive.

Each coupling gear is mounted rotatably, as at 61x, etc., upon a rocker of a series R1 to R9, pivoted upon a shaft 60 (see Fig. 4). These rockers are spaced apart by blocks Rx. The gears 61—69 are prevented from rotating when in their 30 non-driving positions by detent spring Sx. Since the gears 61—69 are constantly in mesh, respectively, with the gears 51—59 of the differentials D1—D9, each of the gears 51—59 is locked against rotation whenever it is not coupled with 35 the associated one of the pinions 21 to 24 on the driving shaft 20.

In further pursuance of the invention a selector means is provided for each differential and is adapted to move each coupling gear of the series 40 61—69 into and out of mesh with the corresponding pinion of the series 21—29 on the driving shaft.

This movement of each coupling gear is effected through its corresponding rocker of the 45 series R1—R9, and a series of springs S1 to S9, is provided, each of which bears against a rocker intermediate its pivot point and the stud upon which the carrier is mounted, tending to bias each carrier toward the position in which it is coupled 50 with its corresponding pinion of the series 21—29 on the driving shaft.

Means to be now described are provided for the purpose of incapacitating any of the differential speed changing mechanisms when the same is 55 not required to be used in delivery of a selected rate of speed.

The preferred selector means comprise a cam shaft 70, Figs. 3, 4, 6 and 10, having thereon cams numbered 71 to 79 inclusive, taking the form of 60 radial discs having peripheral cam surfaces of characteristic shapes. For example, the cam 71 is approximately square but has at a, b, c and d cam surfaces which constitute the high spots of 65 the cam and correspond roughly with the positions of the angles of a quadrangle, slabbed off.

Between a—b, b—c, c—d; and d—a; are the lower points of the cam 71 which, in the instance illustrated are designated respectively e, f, g, and 70 h. These intermediate low spots may be of any suitable shape, and are shown as slightly arcuate.

In Figs. 3 and 10, the high spot "b" of the cam 71 is shown as engaged with the nose n1 of the rocker R1, with the result that the coupling gear 75

61 is positively retracted from the gear 21 on the driving shaft 20.

This position of the rocker R1 and its coupling gear 61 is characteristic of all the gears not in use for delivering a selected speed, and it so happens that in the instance of the illustratively selected speed ratio 2-512, only the gear 62 is coupled to its corresponding actuating gear 22 on the driving shaft 20.

10 There is shown clearly in Fig. 10 of the drawing and does not require further description, so that it need only be added that the cams 72, 73, 74, etc., to 79 inclusive, operate in similar fashion upon the corresponding rockers, to incapacitate them when not required. Accordingly, the selection is negative as to all differential speed changing mechanisms not required, and those in use are spring-biased to operative coupled position, by the springs S1-S9, as already described.

15 20 It will be observed that the cam 72 differs in shape from the cam 71 in the respect that it is of a generally oval shape, and only has two high spots x_1 and x_2 and two lower spots y_1 and y_2 . In the instance illustrated, the rocker R2 has its nose n_2 engaged with the low spot y_1 of the cam 72.

25

It will be observed further that the cam 73 has a still different shape, viz., it has a periphery with one high spot z_1 and one low spot z_2 . In the instance illustrated, the rocker R3 has its nose n_3 engaged with the high spot z_1 of the cam 73 and is thereby held with its gear 63 away from the driving gear 23 on the shaft 20.

30 35 Attention is now called to the fact that desirably the cams on the cam shaft are divided into groups or units, and in the instance illustrated, the cams 71, 72 and 73 constitute a unit which is what may be designated the first unit of the series of cams. The cams 74, 75 and 76 (see Fig. 6) constitute a second unit; and the cams 77, 78 and 79 constitute a third unit; there being three groups of cams or cam units in the instance illustrated, each succeeding group being a duplicate of the first group. With this number of units, having nine cams, it is possible to provide readily for a maximum of 511 combinations of gears, or rather selections of speeds, and this happens to be the number desired in the illustrative example herein shown.

40 45 50 55 55 Reverting to the first cam unit, it is noted that the cams 71, 72 and 73, are mounted on a member 83, with which they may be integral, as shown best in Fig. 6, and the member 83, for the sake of brevity, will be designated a cam-sleeve, and it will be understood that each group of cams is mounted on a similar sleeve as at 84 and 85, so that these sleeves need not be further described in detail.

60 In addition to the cams upon each sleeve there is provided upon the sleeves 83 and 84 respectively a member which constitutes part of a "carry-over" mechanism by which the unit represented by sleeve 84 is at times connected with the sleeve 83, and the sleeve 85 is at times connected with the sleeve 84, for the purpose hereinafter set forth.

65 70 75 In the instance illustrated, the carry-over mechanism is of a known type, in its general composition, and includes a driver 93 which by its peripheral surface 94 normally locks the transfer pinion element 91 by engagement between the teeth 91, which are formed as lateral extensions of alternate teeth of an eight-tooth pinion 86x; these last-named teeth being disposed in alignment with the path of a segmental rack 86 which

is seen in Fig. 10 through a gap 92 in the carry-over member 93 to which it is secured.

The rack 86 and pinion 86x being thus meshed intermittently, at such times the short transfer shaft 87 is rotated, during the setting of the cam-shaft, and the pinion 88 at the other end of the short shaft 87 causes rotation of the full-toothed gear 89 on the sleeve 84, acting to carry-over into the second unit a setting rotation which is a suitable complement of the setting action initiated in the first unit.

By the above described means, the first sleeve 83 is adapted to be rotated for the greater part of its rotative orbit, independently of any of the other cam units, and the latter derive their own rotary movement only from the first cam unit, and only at such times as the interrupted gear 86 is in mesh with the complementary interrupted gear 86x on the short shaft 87. In the instance illustrated, the segmental rack 86 is shown as having four teeth and the pinion 86x as having four locking teeth 91 and eight operating teeth 86x, while the pinion 88 has eight teeth and the gear 89 has thirty-two teeth.

Accordingly, the second sleeve 84 will be rotated one-eighth of a turn for each complete rotation of the member 93 with its four teeth 86, associated with the first group of selector cams, and during rotation of the non-active portion of the member 93 the short shaft 87 and consequently the sleeve 84 and its cams 74, 75 and 76, are maintained inactive. The member 93 and its associated elements constitutes a "Geneva" lock.

In the instance illustrated, there are two short carry over shafts, viz., 87 and 87x (see Fig. 4) so that what has been said with respect to the coupling of the sleeve 83 to the sleeve 84 is to be understood as applying to a similar coupling effect between the sleeve 84 and the third sleeve 85. In other words, at times the sleeve 85 and its associated cams derives its actuation from the sleeve 83 through the sleeve 84 and through the coupling shafts 87 and 87x; while at other times only the sleeves 83 and 84 are rotated and the sleeve 85 remains inactive.

In the operation of the mechanism as a whole, the selector cam shaft 70 will first be set to yield the desired speed ratio, as for example, 2:512, such setting being accomplished by any suitable means, as for example by turning a small hand wheel H (see Fig. 1) which is mounted on the outer end of a shaft 40 that actuates the discs I1, I2 and I3 of the counter I which constitutes the indicator in the instance illustrated and described.

60 65 70 75 80 In the operation of the mechanism for the purpose first of setting it to the selected speed ratio, the rotation of the hand wheel H turns the pinion 80 secured to the shaft 40 and thereby rotates the gear 82, mounted on the cam shaft 70, through the medium of gear 81. When the digits disc I1 of the counter stands at "2", as shown in Fig. 1, the cam shaft 70 will have been turned to the position shown in Fig. 10 with the cam 72 rotated, as illustrated, so that the nose n_2 of the rocker R2 will be pressed by the spring S2 against the low surface y_1 of the cam 102 and consequently the carrier coupling gear 62 will be engaged with the pinion 22 on the driving shaft 20.

Accordingly, the gear 62, which is constantly in mesh with the pinion 52 on the sleeve 50 of the differential D2, is thus coupled to transmit from the driving shaft 20 to the pinion 52 a moment of rotation which is characteristic of the ratio between the number of teeth on driving gear 22 and 76

driven gear 52. The sleeve 50 connected co-rotatively with the gear 52 will communicate its rotation to the gear 52x of differential D2 which will in turn rotate the planetary pinion 42x and planetary pinion 42. The last mentioned planetary pinion is in mesh with the secondary input gear P2 upon the sleeve 9 of differential D1, and inasmuch as the coupling gear 61 is in its incapacitated position, shown in Fig. 10, duplex or primary input gear 51-51x will not be driven by the shaft 20 through coupler 61, but will be locked against rotation by the action of the detent spring S2. Since the gear P1 is a fixed gear which never turns, the spider 31 is locked by the locking of the gear 51-51x. The gear P2 is, as a consequence, locked against rotation, so that there is no input to the spider 32 from P2 and no outlet from the spider 32 through P2.

The pinion 52 will be rotated positively by the coupling gear 62, and its duplex pinion 52x will rotate with it; this will rotate the planetary pinion 42x and the other planetary pinion 42, both of which are mounted on spider 32. As the gear P2 is locked against rotation the planetary pinion 42 will track around the pinion P2 which is fast on the hub of spider 31 (see Fig. 7), and cause the spider 32 to rotate in the same direction as, but at half the speed of the pinion 52, and this rotation will be communicated to the hub 9 of spider 32 and passed on to the pinion P3 of the differential D3; then through the chain of gears in like order, each reducing the speed by half, the output motion will finally be communicated by the dowel pin 10 to the output shaft 38 and thence to the pinion 18, which will be turned at the ratio of 2 R. P. M. to 512 R. P. M. of the shaft driving shaft 20.

Each of the spiders 31 and 39 has theoretically two possible inputs. In the case of spider 31, however, the gear P1 being a fixed or stationary gear, there is never actually any input to the spider 31 from the gear P1. When two elements of a differential are locked the third is locked also. Since P1 is always locked, the locking of 31 locks 31. When the coupling gear 61 is connected to drive 51, however, the spider 31 is not locked but is turned at half the speed of the gear 51, so that the gear P2 turning in unison with the spider 31 is driven forward at half the speed of the gear 51. Now, similarly, the input from the gear 62 through 52 to the spider 32 would be transmitted to the gear P3 to drive the gear P3 at half the speed of the gear 52, if the gear P2 were locked. Since we are now assuming, however, that the gear P2 is not locked, but that it is driven at half the speed of the gear 51, the gear P2 applies its input to the spider 32 and its input is just half that of the gear 52. The input of gear P2 is transmitted to drive 32, and hence gear P3, at half the speed of gear P2, and since the inputs of 52 and P2 are additively combined by the spider 32, the gear P3 is driven at $\frac{3}{4}$ of the speed of the gear 52. Here again, the combination of the inputs of P3 and 53, namely, $\frac{3}{4}$ and $\frac{1}{4}$ will be additively combined and divided by 2 in the transmission to P4, so that the resulting drive there would be $\frac{1}{8}$. If n be taken as the number of differentials, the numbers of available driving ratios is $2^n - 1$, and these ratios form an arithmetical series starting with

$$\frac{1}{2^n}$$

$$2^{n-1}$$

$$2^n$$

and terminating with

All of the rates of speed in the range from 1:512 to 511:512 can be secured by simple rotation of the setting wheel H to the various indicated positions shown at the counter I, in the illustrative embodiment of the invention.

Each position corresponding to the above indications upon the counter, is maintained by the action of a detent roller 99 mounted upon a detent arm 98 supported pivotally at 97 upon the side wall 14 of the casing, the arm 98 being biased by a spring 96 to cause clockwise rotation of the arm 98 toward a star wheel 95 fixed upon the cam shaft 70, best seen in Fig. 3. This star wheel has eight teeth and eight spaces between the teeth, and when the star wheel is turned so that the detent roller 99 bears uniformly against the adjacent surface of any two of the teeth on the star wheel, the shaft 70 is held in such position that any selected cam is disposed with one of the cam surfaces presented toward the nose of a rocker, as R2, standing in the plane of that cam.

In the instance illustrated in Fig. 3, the cam 12, as already described, stands with its low spot y^1 opposite the nose n^2 of the rocker R2 and permits the carrier gear 62 to be forced by spring S2 into mesh with the driving gear 22 on the driving shaft 20.

In the form of construction illustrated in Figs. 12 to 14 inclusive, planetary differential gears using internal gears are employed which may be made smaller and better balanced, and which are more economical to assemble, than planetary differential gears using only external gears.

The structure embodies two banks of differential gears instead of one. The differential assemblies are all identical. The outputs of the two banks are additively combined to make up the output of the unit as a whole. In the process of combining the outputs of the two banks the separate outputs are treated by gear ratios so that the output of one bank upon the combined output is twice that of the other.

The reason for employing two banks of differentials and for giving one bank twice the effect of the other arises from the type of differential gears which are employed in this embodiment of the invention.

It is not possible with planetary differential gears of the internal gear type, without using compound planetary gears, to make the step from one differential to the next in the ratio of 2:1, it being necessary to make the step some ratio greater than 2:1. In the illustrated embodiment a ratio of 4:1 has been chosen. With each step representing a 4:1 ratio it is evident that if a value of 1 be given to the differential having the least effect upon the output, the successive differentials of the same bank will bear relations to this first differential represented by successive powers of 4. Successive powers of 4 cannot be added to one another or combined in any way to give a continuous series including all integral numbers from 1 up to the sum of the several powers. For example, between 1 and 4 there is no way of securing 2 and 3. With 1, 4, 16 and 64 only 1, 4, 5, 16, 17, 20, 21 etc., can be secured.

By providing a second similar bank, however, which starts with 2, values of 2, 8, 32 and 128 may be secured. Thus, by alternating between the two banks it will be seen that a differential is provided representing each power of 2 from the zero power to the seventh power. The numbers of this series can be combined without using any

one of them more than once to secure any integral number from 1 to 255.

The differentials are all selectively driven from a common source represented illustratively by an input crank handle 101 which turns an input shaft 102. The input shaft carries the series of gears W2, W8, W32, and W128 which may be coupled selectively, either simultaneously or separately, through transmission gears T2, T8, T32 and T128 to drive internal gears I2, I8, I32 and I128, respectively, which form elements of the differentials of one bank. The motion of shaft 102 is transmitted through bevel gears 103 and 104 to a cross shaft 105 and thence through bevel gears 106 and 107 to a shaft 108. The shaft 108 turns at the same speed but in the opposite direction from the shaft 102. The shaft 108 has fast upon it a series of gears W1, W4, W16 and W64 which may be coupled, respectively, through transmission gears T1, T4, T16 and T64, to associated internal gears I1, I4, I16 and I64 forming elements of the differential gears of the other bank. The object of the entire mechanism is to transmit motion at a selected rate or ratio from the shaft 102 to the output shaft 109 of the apparatus.

The rate selecting mechanism is illustratively shown as controlled from a finger wheel 110 upon a shaft 111 which, through suitable gearing represented by 112, 113, and 114, drives a shaft 115. The shaft 115 has a series of cams 116 upon it, each of different and appropriate contour, for controlling through a cam follower 117 the connection and disconnection of a gear, as W2, on the shaft 102, with its associate internal gear, as I2, of the right hand bank of differentials. Only one cam is illustrated, and this diagrammatically. The shaft 115 acts through bevel gears 118 and 119 to drive a shaft 120, and the shaft 120 in turn acts through bevel gears 121 and 122 to drive a shaft 123. The shaft 123 carries cams 124 for acting upon followers 125, to connect and disconnect the differentials of the left hand bank with the shaft 108. One cam 124 is provided for each differential train and each cam may be of different contour, appropriate to the particular location of it in the machine. By providing a Geneva lock, however, a number of like groups of cams can be used as before.

If it be assumed that one revolution of the shaft 108 acting through the gear I1 imparts to the shaft X1 a unit of revolution x then a single rotation of the shaft 108 will impart the same unit of revolution of rotation to the shaft X4 through the gear I4, to the shaft X16 through the gear I16, and to the shaft X64 through the gear I64. Since one revolution of the shaft X1 produces only $\frac{1}{4}$ revolution of the shaft X4, however, and this same numerical relationship exists between the shaft X4 and shaft X16 and between the shaft X16 and the shaft X64 a single revolution of the shaft 108 transmitted through the gear I1 will impart x revolutions to the shaft X1

65
$$\frac{x}{4}$$

revolutions to the shaft X4,

70
$$\frac{x}{16}$$

revolutions to the shaft X16 and

75
$$\frac{x}{64}$$

revolutions to the shaft X64. Thus a single revolution of the shaft 108 transmitted through the gear I64 will produce 64 times as much angular movement of the shaft X64 as one revolution of the shaft 108 transmitted through the gear I1 and thence to the shaft X64 through the successive differential gears.

The right hand bank of differentials being identical with the other bank, the same numerical relations will exist. Although the drives to the shafts X64 and X128 are identical, the shaft X128 is coupled to have twice as great an effect upon the output shaft 109 as the shaft X64 has, and hence all of the differentials of the right-hand bank, as compared with the corresponding differentials of the left-hand bank, are multiplied in effect by 2. A single revolution of the crank handle 101 transmitted through the gear I128 will have 128 times the effect of a single revolution of the crank handle transmitted through the gear I1.

The rate controlling mechanism is designed to change the rate by unit steps, without gaps, from 1 to 255, all numbers being over the same common denominator whose value is unimportant since it can be changed in the output by any form of gearing or other uniform connecting train desired.

In order to accomplish this result, the rate changing cams are so constructed, designed and operated that the gear I1 will be connected at alternate steps. The gear I2 will be disconnected for the first step and will thereafter be connected for two steps, then disconnected for two steps, and so on in continuous alternation. Similarly the gear I4 will be disconnected for the first three steps then connected and disconnected alternately throughout series of four successive steps. Gear I8 will come into operation at the eighth step, will remain connected for 8 steps then be disconnected for 8, and so on. The law governing the control of the other differentials is sufficiently indicated by these illustrations. It will be understood that the cam arrangement may be similar to that shown in Figs. 3 and 4 in which they are arranged in groups with suitable gearing between them.

The details of construction of the mechanism are illustrated in Figs. 13 and 14. Stationary shafts 126 and 127 support, respectively, shafts X1, X4, X16 and X64 of the left hand bank and shafts X2, X8, X32 and X128 of the right hand bank. The differential units are all alike and hence a description of one of them, as illustrated in Fig. 14, will suffice for all, it being understood that corresponding letters are applied to corresponding parts in all of the units but that the subscripts of the letters are made to correspond with the units in which the parts are used. The shaft X16 has fast upon it a sun gear S64. The hub of internal gear I64 is journaled upon the shaft X16. The internal gear I64 is constantly in mesh with the transmission gear T64 which as already pointed out may be coupled to and uncoupled from the shaft 108 at will. An epicyclic or planet gear E64 is rotatably carried by an arm A64 integral with the shaft X64. The gears E64 and S64 are of equal diameters and have equal numbers of teeth. The gear I64 has an internal pitch diameter three times as great as the pitch diameter of the gear S64 and has three times the number of teeth of the gear S64. When the shaft X16 is held stationary and the gear I64 is driven, one revolution of the gear I64 will produce $\frac{3}{4}$ of a revolution of the arm A64 and hence of the

shaft X64. When the gear 164 is held stationary and the shaft X16 is driven one revolution of the shaft X16 will produce $\frac{1}{4}$ of a revolution of the shaft X64. Since one revolution of gear 116 will produce $\frac{3}{4}$ revolution of the shaft X16 it will be seen that one revolution of the gear 116 will produce $\frac{3}{16}$ of a revolution of the shaft X64 as against the $\frac{3}{4}$ of a revolution produced by one revolution of the gear 164, the ratio of output through gear 116 to output through gear 164 being as previously pointed out $\frac{1}{4}$.

While the units have been referred to as all exact duplicates, it is to be noted that the sun gear S1 is mounted upon a shaft X0 which is permanently held against rotation, and that the sun gear S2 is similarly mounted upon a shaft X0 which is permanently held against rotation. It is also to be noted that the shaft X64 has fast upon its forward end an output gear 130 in place of the usual sun gear, and that the shaft X128 has fast upon its forward end an output gear 131 in place of the usual sun gear.

The shafts 126 and 127 are supported between frame members 132 and 133. A suitable spacer sleeve 134 is interposed between the frame member 133 and the gear 130 on the shaft 126 and affixed to the shaft by a set screw 135. A similar spacer sleeve 136 is interposed between the frame member 133 and the gear 131 upon the shaft 127 and affixed to the shaft by a set screw 137.

It will be remembered that the shaft 108 rotates in the opposite direction from the shaft 102. In order that the output of shaft X64 may be additively combined with the output of shaft X128, a transmission pinion 138 is interposed between the gear 130 and an output gear 139, while the gear 131 meshes directly with an output gear 140. The output gears 139 and 140 are arranged to drive the output shaft 109 through a differential gear 141 which is identical with the differential gears employed in the two banks of gears. The gear 139 is integral with a hollow shaft Xd which is journaled upon the output shaft 109 and which carries a sun gear Sd at its forward end. The gear 140 is fast upon the hub of an internal gear Id. An epicyclic or planet gear Ed is rotatably carried by an arm Ad whose hub is fixed to the shaft 109 by means of a pin 142.

Having in mind that the effect of one revolution of the gear Id upon the shaft 109 when the gear Sd is stationary would be to drive the shaft 109 $\frac{3}{4}$ of a revolution, whereas the effect of one revolution of the shaft Xd while the gear Id is stationary would be to drive the shaft 109 through $\frac{1}{4}$ of a revolution, it is evident that some provision must be made in the gear connections 131, 140 and in the gear connections 130, 138, 139 for causing one revolution of the shaft X128 to rotate the shaft 109 twice as far as one revolution of the shaft X64 rotates the shaft 109.

In the illustrative mechanism the gears are so chosen that one revolution of the shaft X64 produces $\frac{3}{4}$ of a revolution of the shaft Xd thereby producing $\frac{1}{3}$ of a revolution of the shaft 109. The value of the denominator is unimportant, the important point being that the ratios have common denominators and that their numerators are in the ratio of 2 to 1.

While the drive ratio of 1-4 between successive differential units has been chosen herein and spoken of as illustrative, that ratio is regarded

as excellently suited to the present purpose. As pointed out, the ratio must be greater than 2 to 1. 3 to 1 would be a suitable and operative ratio, but with the illustrative number and arrangement of the differentials, the differentials of the left hand bank instead of having relative values 1-4-16-64 would have relative values 1-3-9-27 and the differentials of the right hand bank would have values 2-6-18-54, which would only yield possible rates of driving speed running from 1 to 120 or less than one-half the range of the illustrative apparatus. With a ratio of 5 to 1 or any greater ratio, on the other hand, more than two banks of differentials would be required in order to avoid gaps in the series of possible ratios.

The principle of the invention is, however, regarded as comprehending a structure in which more than two banks of differentials are employed, as for example, a three-bank machine in which successive differentials of a bank bear the relation of 1-8 and in which the several banks have the relative weights of 1 to 2 to 4, or a four bank machine in which the successive differentials of a bank bear the relation of 1-16 and in which the several banks have the relative weights of 1 to 2 to 4 to 8 and so on.

I have described what I believe to be the best embodiments of my invention, I do not wish, however, to be confined to the embodiments shown, but what I desire to cover by Letters Patent is set forth in the appended claims.

I claim:

1. Speed changing mechanism; comprising a driving member; a driven member; a multiplicity of like differential gears intermediate said members arranged in a group and constantly coupled to one another in such manner that each differential of the group other than the first receives the entire output of its predecessor in the group for reduction in a predetermined ratio and transmission to the driven member, whereby the individual output values of the differentials from the first to the last of the group are caused to form a geometrical series, and means for independently coupling the individual differentials selectively with the driving member in various combinations, to derive various speeds from said driving member and to deliver to said driven member a greatly multiplied range of resultant speeds, including means to compel the various possible ratios of input to output to be established in continuously ascending or continuously descending order.

2. Speed changing mechanism; comprising a driving member; a driven member; a multiplicity of like differential gears intermediate said members arranged in a group and constantly coupled to one another in such manner that each differential of the group other than the first receives the entire output of its predecessor in the group for reduction in a predetermined ratio and transmission to the driven member, whereby the individual output values of the differentials from the first to the last of the group are caused to form a geometrical series, and means for independently coupling the individual differentials selectively with the driving member in various combinations, to derive various speeds from said driving member and to deliver to said driven member a greatly multiplied range of resultant speeds, including means to compel the various ratios of input to output to occur in a sequence forming an arithmetical series, and means to indicate visually the speed which is established.

3. Speed changing mechanism: comprising a driving member; a driven member; a multiplicity of like differential gears intermediate said members so connected to one another that these individual output ratios form a geometrical series and adapted to be coupled selectively with said input member individually and in combinations with each other to derive various speeds from said driving member which form an unbroken arithmetical series, and selector means to effect selection and coupling of the particular gear or combination of gears required to deliver any desired rate of speed in the available range thereof, said selector means arranged to compel the various speeds to be established in continuously ascending or descending order and including a plurality of like cam units, each including a plurality of individual differential controlling cams, and Geneva carry-over means for operating one unit from the next, step by step.
4. Speed changing mechanism: comprising a driving member; a multiplicity of differential gear units, each unit including two input gears and an output gear; also a coupling gear in mesh with one of said input gears, and movable into and out of a coupled position with said driving member; a driven member; means for moving said coupling gears selectively to and from their coupling positions respectively; means for coupling said differential units to each other in predetermined order; and means for coupling their output gears to said driven member, thereby to effect the delivery to said driven member of a motion combining the motions impressed upon the several input gears, to yield any of a wide range of speeds available by the use of said differentials, and selector means to effect selection and coupling of the particular gear or combination of gears required to deliver any desired rate of speed in the available range thereof, said selector means arranged to compel the various speeds to be established in continuously ascending or descending order and including a plurality of like cam units, each including a plurality of individual differential controlling cams, and Geneva carry-over means for operating one unit from the next, step by step.
5. Speed changing mechanism: comprising a driving member; a multiplicity of differential gear units, each unit including two input gears and an output gear; also a coupling gear in mesh with one of said input gears, and movable into and out of a coupled position with said driving member, means for locking the coupling gear when it is disconnected from the driving member, a driven member; means for moving said coupling gears selectively to and from their coupling positions respectively; means for coupling said differential units to each other in predetermined order; and means for coupling their output gears to said driven member, thereby to effect the delivery to said driven member of a motion combining the motions impressed upon the several input gears, to yield any of a wide range of speeds available by the use of said differentials, and selector means to effect selection and coupling of the particular gear or combination of gears required to deliver any desired rate of speed in the available range thereof, said selector means arranged to compel the various speeds to be established in continuously ascending or descending order and including a plurality of like cam units, each including a plurality of individual differential controlling cams, and Geneva carry-over means for operating one unit from the next, step by step.
6. Speed changing mechanism: comprising a driving member; a multiplicity of differential gear units, each unit including two input gears and an output gear; also a coupling gear in mesh with one of said input gears, and movable into and out of a position in which it is coupled with said driving member; a driven member; means for moving said coupling gears selectively to and from their coupling positions respectively; means for coupling said differential units to each other in predetermined order; and means for coupling their output gears to said driven member, thereby to effect the delivery to said driven member of a motion combining the motions impressed upon the several input gears, to yield any of a wide range of speeds available by the use of said differentials, a rocker for and to support each of said coupling gears individually, and a cam-shaft having a series of cam discs each engaged with one of said rockers.
7. Speed changing mechanism: comprising a driving member; a multiplicity of differential gear units, each unit including two input gears and an output gear; also a coupling gear in mesh with one of said input gears, and movable into and out of a position in which it is coupled with said driving member; a driven member; means for moving said coupling gears selectively to and from their coupling positions respectively; means for coupling said differential units to each other in predetermined order; and means for coupling their output gears to said driven member, thereby to effect the delivery to said driven member of a motion combining the motions impressed upon the several input gears, to yield any of a wide range of speeds available by the use of said differentials, a rocker for and to support each of said coupling gears individually, and a cam-shaft having a cam disc engaged with each of said rockers, said cam-shaft having a star-wheel fixed thereon; and a detent to hold said star-wheel yieldingly in each position of each cam.
8. Speed changing mechanism: comprising a driving gear-shaft; a driven gear-shaft; a multiplicity of speed-changing gear units adapted to transmit motion from said driving shaft to the driven shaft, the individual outputs of said units forming a geometrical series, coupling members individual to said units and operable individually to and from effective positions, and a selector means including a cam shaft having a plurality of cams thereon, each individually controlling one of the gear units low in the scale of output values, an additional like cam shaft having like cams for controlling similarly related units higher in the scale of output values, and Geneva carry-over mechanism for operating the second cam shaft from the first after a plurality of steps of the first equal to the ratio of output values of gear units controlled by corresponding cams of the two shafts.
9. A selector mechanism for effecting changes of speed automatically throughout a wide range of available rates of speed deliverable at the driven member in a speed-changing mechanism of the class described; said selector mechanism comprising a plurality of cam units each comprising a plurality of cam devices co-axially disposed along a common axis and rotatable in unison, means for rotating the first unit, and carry-over mechanism for operating the second unit periodically from the first.
10. A selector mechanism for effecting changes of speed automatically throughout a wide range of available rates of speed deliverable at the driven member in a speed-changing mechanism of the class described; said selector mechanism comprising a series of cam units each comprising a plurality of cam devices co-axially disposed along a common axis and rotatable in unison, means for rotating the first unit, carry-over

mechanism for periodically operating the second unit from the first and for locking the second unit against operation throughout the remainder of each cycle of the first, and carry-over mechanism for similarly operating the third unit from and in relation to, the second.

11. A selector mechanism for effecting changes of speed automatically throughout a wide range of available rates of speed deliverable at the driven member in a speed-changing mechanism of the class described; said selector mechanism comprising a plurality of cam units comprising a plurality of cam devices rotatable in unison and co-axially disposed along a common axis, means for operating one of said units through a predetermined series of steps constituting a cycle independently of operation of any other unit, during which cycle the selector cam surfaces of said unit are made effective, and means to operate another of the units periodically from the first through a similar cycle, but only one step for each cycle of the first, to make effective cam surfaces in more than one unit with a consequent selection of additional rates of speed throughout the entire available range of rates of speed, said selective operations being each a linear function of the simple rotation of the cam shaft.

12. A selector mechanism for effecting changes of speed automatically throughout a wide range of available rates of speed deliverable at the driven member in a speed-changing mechanism of the class described; said selector mechanism comprising a cam shaft carrying a multiplicity of cam devices co-axially disposed along a common axis and divided into at least two units, at least one of said units having a predetermined movement of rotation independently of any other unit, and during which movement one or more selected cam surfaces of said unit are made effective, and a locking member between each two adjacent groups, whereby the selector system is so controlled that only the group or groups anterior to each lock can be affected by rotation of the selector system prior to release of the locking member.

13. A selector mechanism for effecting changes of speed automatically throughout a wide range of available rates of speed deliverable at the driven member in a speed-changing mechanism of the class described; said selector mechanism comprising a cam shaft carrying a multiplicity of cam devices co-axially disposed along a common axis and divided into at least two units of which at least one unit has a predetermined movement of rotation independently of any other unit, and during which movement one or more selected cam surfaces of said unit are made effective; and a locking member between each two adjacent groups, whereby the selector system is so controlled that only the group or groups anterior to each lock can be affected by rotation of the selector system prior to release of the locking member, and the release of each lock in its turn is effected by the normal, unidirectional rotation of the cam assembly.

14. A selector mechanism for effecting changes of speed automatically throughout a wide range of available rates of speed deliverable at the driven member in a speed-changing mechanism of the class described; said selector mechanism comprising a cam shaft carrying a multiplicity of cam devices co-axially disposed along a common axis and divided into at least two units, with locks therebetween so that at least one unit has a predetermined movement of rotation in- dependently of any other unit, and during which movement one or more selected cam surfaces of said unit are made effective, said locks being so disposed and arranged as to be operated in reverse upon backsetting of the cam assembly.

15. A selector mechanism for effecting changes of speed automatically throughout a wide range of available rates of speed deliverable at the driven member in a speed-changing mechanism of the class described; said selector mechanism comprising a cam shaft carrying a multiplicity of cam devices co-axially disposed along a common axis and divided into at least two units of which at least one unit has a predetermined movement of rotation independently of any other unit, and during which movement one or more selected cam surfaces of said unit are made effective, one cam in each unit having a series of four high surfaces on its periphery, alternating with four low surfaces; another cam in each unit having two high surfaces and two low surfaces; and a third cam in each unit having one high surface and one low surface.

16. A selector mechanism for effecting changes of speed automatically throughout a wide range of available rates of speed deliverable at the driven member in a speed-changing mechanism of the class described; said selector mechanism comprising a cam shaft carrying a multiplicity of cam devices coaxially disposed along a common axis and divided into at least two units, at least one of said units having a predetermined movement of rotation independently of any other unit, and during which movement one or more selected cam surfaces of said unit are made effective, and means to couple a plurality of said units together to make effective cam surfaces in more than one unit, with a consequent selection of additional rates of speed throughout the entire available range of rates of speed, said coupling means each including a locking member, an interrupted gear associated with one of said locking devices on an early unit in the series, a complete gear on a later unit in the series, and a short shaft parallel with the cam shaft and having a pinion in mesh with said complete gear at all times, and having an interrupted gear complementary to the first-named interrupted gear, and a locking member complementary to the locking member on the unit.

17. Speed changing mechanism; comprising a driving shaft having peripheral pinion-gears means adapted to be meshed at a multiplicity of regions along its length by a series of carrier gears to be driven thereby; a driven shaft parallel with said driving shaft; a multiplicity of differential units associated with said driven shaft, and each including a spider mounted rotatably upon the driven shaft, each spider having a hub, with a pinion fixed on the hub and adapted to mesh with one of said carrier gears, and a second pinion fixed on the hub and spaced co-axially from said first pinion, a first planetary gear on said spider and adapted to track around one of said hub pinions, a second planetary gear on said spider meshing with said first planetary gear, a third pinion co-axially disposed relatively to said spider hub and the driven shaft, and in mesh with said second planetary gear, serving as a sun gear therefor, and a fourth pinion fixed upon the hub of said spider and adapted to drive said hub; a series of carrier gears of which one is always in mesh with said fourth pinion; and a selector means adapted to move each carrier gear into and out of mesh with said corresponding

- fourth pinion; each differential unit having its above-named components so disposed that when said fourth pinion is rotated by its carrier it supplies an input of predetermined rate to the driven shaft system, acting through the third pinion upon the first planetary gear, then upon the second planetary gear, to cause said second planetary gear to track upon a fifth pinion and thus to rotate the spider, each spider acting to impart to the primary input pinion of a posterior or succeeding differential in the system an input which is the resultant of the combined motions of the preceding differentials in the series, the pinion which serves as the track for the second planetary gear of the first differential being fixed against rotation, and the last spider of the series being fixed upon the driven shaft.
18. A speed changing mechanism comprising an input member, an output member, and means for selectively controlling the driving ratio from the input to the output member comprising series of differential gears arranged in two banks, means for establishing a driving connection between the input member and each differential independently of the other differentials, the output ratios of the individual differentials of each bank forming a geometrical series, each bank including output means combining the outputs of all the differentials of the bank and connections between the banks and the output member for additively combining the outputs of the banks and for causing the output of one bank to be transmitted to the output member in a definite ratio and the output of the other bank to be transmitted to the output member in double that ratio.
19. A speed changing mechanism comprising an input member, an output member, and means for selectively controlling the driving ratio from the input to the output member comprising series of epicyclic differential gears arranged in two banks, means for establishing a driving connection between the input member and each differential independently of the other differentials, the output ratios of the individual differentials of each bank forming a geometrical series, each bank including output means combining the outputs of all the differentials of the bank and connections between the banks and the output member for additively combining the outputs of the banks and for causing the output of one bank to be transmitted to the output member in a definite ratio and the output of the other bank to be transmitted to the output member in double that ratio.
20. A speed changing mechanism comprising an input member, an output member, and means for selectively controlling the driving ratio from
- the input to the output member comprising series of differential gears arranged in two banks, means for establishing a driving connection between the input member and each differential independently of the other differentials, the output ratios of the individual differentials of each bank forming a geometrical series, each bank including output means combining the outputs of all the differentials of the bank and connections between the banks and the output member for additively combining the outputs of the banks and for causing the output of one bank to be transmitted to the output member in a definite ratio and the output of the other bank to be transmitted to the output member in double that ratio, and means combining the outputs of all the differentials of the bank and connections between the banks and the output member for additively combining the outputs of the banks and for causing the output of one bank to be transmitted to the output member in a definite ratio and the output of the other bank to be transmitted to the output shaft in double that ratio, and means connecting each differential gear of each bank other than the first to be driven by its predecessor in the bank in the ratio of 1 to 4.
21. A speed changing mechanism comprising an input member, an output member, and means for selectively controlling the driving ratio from the input to the output member comprising series of differential gears arranged in two banks, and connections between the banks and the output member for additively combining the outputs of the banks and for causing the output of one bank to be transmitted to the output member in a definite ratio and the output of the other bank to be transmitted to the output shaft in double that ratio, and means for coupling each differential to be driven from the input member independently of the other differential gears and for causing the output of each differential gear of each bank, other than the last, to be constantly transmitted to its successor in a predetermined ratio.
22. A speed changing mechanism comprising an input member, an output member, and a rate changing member for controlling the rate of output to input, driving connections for selectively coupling the input and output members in different ratios comprising series of differential gears arranged in two parallel banks and all connected to operate the output member, a pair of parallel driving shafts connected to be operated invariably by the input member and disposed adjacent the respective banks of differential gears, and means for selectively connecting the differential gears each to be driven from the associated driving shaft comprising parallel controlling shafts disposed alongside the respective driving shafts, and driven in common from the rate changing member, and connection controlling members carried by said controlling shafts.

PETER J. McLAREN.
